[57] CLAIM

The ornamental design for combination rain pants and gaiters, as shown and described.

DESCRIPTION

FIG. 1 is a perspective view from the front of the combination rain pants and gaiters of my design;

FIG. 2 is a rear elevational view of the combination rain pants and gaiters of FIG. 1;

FIG. 3 is a broken away view in perspective of the gaiters of the combination rain pants and gaiters of FIG. 1;

FIG. 4 is a front elevational view of the gaiters of FIG. 3;

FIG. 5 is a side elevational view of the gaiters of FIG. 3;

FIG. 6 is a rear elevational view of the gaiters of FIG. 3;

FIG. 7 is a broken away view in front elevation of the rain pants of the combination rain pants and gaiters of FIG. 1; and,

FIG. 8 is a rear elevational view of the rain pants of FIG. 7. The broken line showing of a persons waist in FIG. 1, and of partial legs in FIG. 3, is for illustrative purposes only and forms no part of the claimed design.
